UNITED STATES PATENT OFFICE.

EMILY C. CUSHING, OF DENVER, COLORADO.

DISPLAY RACK.

Application filed May 2, 1925. Serial No. 27,539.

To all whom it may concern:

Be it known that I, Mrs. EMILY C. CUSHING, a citizen of the United States, residing at Denver, in the county of Denver and

5 State of Colorado, have invented a new and useful Display Rack, of which the following is a specification.

This invention relates to display racks of the revoluble type.

10 The object of the invention is to provide a simple and efficient device of this character constructed to effectively display cards, merchandise and the like and which is revoluble to exhibit all sides by turning the rack around.

Another object of the invention is to construct a rack of this character which is simple, strong and durable and which is readily portable from one place to another.

20 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

30 In the accompanying drawings:

Figure 1 represents a top plan view of a rack constructed in accordance with this invention;

Fig. 2 is a horizontal section with parts broken out;

Fig. 3 is a front elevation; and

Fig. 4 is a detailed vertical section taken on the line 4—4 of Fig. 3.

40 In the embodiment illustrated, the rack constituting this invention is shown mounted on a base 1 composed of any suitable material, preferably of wood and to the upper face of which is secured a metal plate 2 having a post 3 rising therefrom and equipped with a socket 4 to receive a shaft 5 which is fixedly mounted in said socket and on which the display rack or cage 10 is revolubly mounted.

50 This display rack or cage 10 is composed preferably of wire of different sizes bent to form the various elements of the cage which include rectangular upper and lower members 11 and 12 to which are secured respectively spiders 13 and 14 each constructed exactly alike and each composed of metal plates or strips 15 which intersect each other

midway their length forming a cross with their ends rolled to form bearings or gripping elements for connection with the members 11 and 12.

60

These spiders 13 and 14 have openings at the points of intersection of the plates 15 for the passage therethrough of the shaft 5. The upper end of the shaft has a collar 6 arranged below the spider 13 and a head 7 arranged above it so that the cage is supported on the upper end of the post 3 and between the collar 6 and head 7.

65

Rods 17 rise from the corners of the member 12 and are connected at their upper ends to the corners of member 11, these rods 17 are preferably so connected by bending their ends to form eyes 18 which are soldered to the members 11 and 12 to form a rigid connection at these points.

75

Four card supporting members are carried by the four faces of the frame or cage and are constructed exactly alike so that one only will be described in detail.

Each of these holders or supports comprises an upper cross bar 19 and a lower cross bar 20 formed of wire of smaller gage than the top and bottom members 11 and 12 and which are provided at their ends with inwardly extending loops 21 which are hooked around the rod 17 at the corners of the frame and preferably soldered thereto. These cross bars are arranged in a plane within that occupied by the members of the top and bottom portions of the frame. 90 These loops 21 at the ends of bars 19 and 20 are connected at their free ends by upstanding rods 22. The loops of the respective card supports at each corner extend one in one direction and one in the other and 95 overlie each other forming guides or retainers for the edges of cards to be supported.

These card holders are preferably constructed from a single piece of wire bent to form the element just described which is 100 united at its ends by soldering or otherwise and from the center of the cross bars extend rods 23 having their ends bent to form eyes which engage the cross bars at the top of the frame and which are arranged in a plane 105 spaced inwardly from that occupied by the rod 22 and form supports for the back of the cards to be exhibited.

The loops 21 of one of the card supporting members extend in one direction while 110 those of the adjacent side extend in the opposite direction and overlie each other, be-

ing preferably soldered to the rod 17. These loops are arranged substantially parallel with their respective rods and form with said rods guides for the side edges or ends of the cards to be exhibited. To support the bottom edges of the cards to be exhibited are supports 24 one carried by each of the bottom members 20 and formed of a piece of wire having laterally extended ends 25 bent midway their length to form loops 26 which extend around the side bars of the bottom member 12 and have their terminals equipped with eyes 27 engaged with the bar or rod 20 one being located at one side of the centrally disposed rod 23 and one at the other as is shown clearly in Fig. 3.

A handle 28 is secured to the upper portion of the frame and extends upwardly therefrom being preferably composed of a piece of heavy wire bent to form a centrally disposed coil 29 with the ends or arms 30 thereof extending downwardly and equipped at their terminal with eyes 31 which engage the side members of the top frame 11 at the points of connection of the spider arms therewith, said eyes being preferably soldered at this point to render the handle rigid.

The coil 29 may also be used to support cards to be displayed which may be inserted between the members of the coil so that this handle 28 will perform a double function.

From the above description it will be obvious that the cards to be supported which may or may not have merchandise attached to them are inserted between the rods 22 and 23 with the side edges of the cards located under rods 22 and their ends inserted between the loops 21 and the rods 19

and 20, their lower edges being supported in the pockets formed by the members 24. These racks may be readily transported from place to place owing to their light construction and the ready means for handling them.

I claim:

1. In a display rack, a supporting base, a skeleton frame mounted to revolve on said base, card supporting members carried by said frame and comprising upright laterally spaced guides with a seat at the bottom, said guides being composed of upper and lower cross bars formed of wire arranged in a plane within that occupied by the members of the frame having loops one extended in one direction and one in the other and overlying each other to form guides or retainers for the edges of the cards to be supported, and supporting wires carried by the lower ends of the frame and bent to form pockets to receive the bottom of the card.

2. A display rack comprising a frame including an upright revoluble member composed of wire and including spiders at its upper and lower ends, a post extending through said spiders and on which the frame revolves, card supporting members carried by said frame and each composed of an upper and a lower cross bar having loops engaged with members of the frame at the corners thereof, said cross bars being arranged in a plane within that occupied by the members of the frame.

In testimony that I claim the foregoing as my own, I have hereto affixed my signature.

EMILY C. CUSHING.
